UNITED STATES PATENT OFFICE.

SYLVESTER A. DRAKE, OF JAMESTOWN, NEW YORK.

POULTRY-FEEDER.

1,131,491.

Specification of Letters Patent.

Patented Mar. 9, 1915.

Application filed April 4, 1914. Serial No. 829,552.

To all whom it may concern:

Be it known that I, SYLVESTER A. DRAKE, a citizen of the United States, residing at Jamestown, in the county of Chautauqua and State of New York, have invented new and useful Improvements in Poultry-Feeders, of which the following is a specification.

This invention relates to poultry feeders, and it has for its object to provide a device 10 of simple and improved construction whereby different varieties of feed, such as fine grits and coarse grain, mash and other coarse feed may be simultaneously fed or supplied and in which provision is made for 15 regulating the supply of the relatively coarse food without affecting the manner in which the relatively fine food is supplied.

A further object of the invention is to provide a feed tray in combination with a hopper which is supported adjustably with respect to said feed tray, simple and improved supporting means being provided whereby the hopper may be adjustably supported.

A still further object of the invention is to provide in connection with the improved feed device a guard whereby access to the feed tray will be partly obstructed to prevent young chicks from jumping into the tray and wasting the food; said guard being dispensed with when the device is used for feeding older fowls.

With these and other ends in view which will readily appear as the nature of the invention is better understood, the same consists in the improved construction and novel arrangement and combination of parts which will be hereinafter fully described and particularly pointed out in the claims.

In the accompanying drawings has been illustrated a simple and preferred form of the invention, it being, however, understood that no limitation is necessarily made to the precise structural details therein exhibited, but that changes, alterations and modifications within the scope of the claims may be resorted to when desired.

In the drawings,—Figure 1 is a perspective view of a device constructed in accordance with the invention. Fig. 2 is a top plan with the lid or cover removed. Fig. 3 is a vertical section taken on the line 3—3 in Fig. 2. Fig. 4 is a horizontal sectional detail view taken on the line 4—4 in Fig. 3, the guard device including the bars 21 hav-

ing been detached. Fig. 5 is a perspective view of the tray, detached.

Corresponding parts in the several figures are denoted by like characters of reference.

1 designates a tray which has been shown as being of circular shape, said tray being provided with a circumferential upstanding flange 2 and with a conical bottom member 3. Supported upon and extending upwardly from the conical bottom portion are 60 upstanding wall members 4 constituting partitions which coöperate with the hopper to be presently described to form two or more compartments 5, 6, the latter being much the largest. The wall members 4 65 which are radially disposed with respect to the bottom member are provided at their lower ends with flanges constituting partitions 7 which are of a height corresponding with that of the flange 2 with which they 70 are connected.

The wall members 4 are slightly tapered in an upward direction to correspond with a slightly tapered hopper 8 which surrounds said wall members and which is supported a 80 short distance above the tray. The latter is provided with upwardly extending rods 9 having at their upper ends plates 10, each of which is provided with a plurality of perforations 11 adapted to engage pins 12 85 which extend inwardly from the wall of the hopper. The latter may thus be supported at various distances above the tray, and the distance may be quickly and easily varied by shifting the relative positions of 90 the pins 12 and the perforated plates 10. The rods 9 are of a resilient nature so that the perforated plates may be readily sprung into and out of engagement with the pins 12. The hopper is provided adjacent to its 95 lower edge with notches 13 engaging the flanges or partitions 7, so that the latter will not interfere with the vertical adjustment of the hopper, which latter may be lowered until the lower edge thereof is nearly or 100 quite in contact with the tray. It is obvious that by such adjustment the passage of material from the compartments of the hopper in the direction of the flange 2 of the tray may be regulated or entirely obstructed, 105 as may be desired.

The walls or partition members 4 are provided at their outer edges with flanges 14 which are formed by bending the outer portions of said partition members at an obtuse 110

angle to the radial portions of said partition members. The latter, being usually and preferably constructed of sheet metal having a certain degree of inherent resiliency, it follows that the outer edges of the flanges will abut upon the inner face of the wall of the hopper in various positions of the latter, thus causing the walls or partition members 4 in connection with the wall of the hopper 10 to form the compartments 5 and 6 hereinbefore referred to. It is obvious that in order to secure the best results, the taper of the hopper and the corresponding taper of the wall members 4 should be very slight; 15 when such is the case the flanges of the wall members will engage the wall of the hopper sufficiently close to cause material placed in the various compartments to be retained therein, except as it feeds between the lower edge of the hopper and the bottom of the tray, the object being simply to keep the contents of the several compartments separated.

The smaller compartments 5 are intended 20 to contain relatively fine feed, such as grits and the like, while the other compartments may contain coarse feed, such as grain, mash, chopped vegetables or the like. In order to prevent the relatively fine material 25 from being supplied too rapidly when the hopper is adjusted for coarse feed, the flanges or partitions 7 are connected together by bridge pieces 15 which are spaced the desired distance above the bottom of the tray, said bridge pieces being curved to conform with the contour of the hopper.

The hopper is provided with a tightly fitting lid 16, and it has a bail 17 whereby it may be carried, said bail being formed with 30 a ring or eye 18 with which a rope or cord may be connected for the purpose of suspending the feeding device in a slightly elevated position above the ground, thereby preventing the access thereto of dirt and 35 vermin.

A guard is provided which is composed of two rings or hoops 19, 20 encircling respectively, the hopper 8 and the flange 2, said hoops being connected together by spacing rods 21. This guard when applied to 40 the feeding device is detachably supported upon the flange 2 of the tray with which the spacing rods 21 contact. When thus applied, young chickens that are being fed will 45 be kept spaced apart and will also be prevented from jumping into the tray and wasting the feed. When the device is used for feeding older chickens, the guard may be detached.

50 This improved device is simple in construction, and it has been found very convenient for feeding the various kinds of food

with which chickens should be supplied. The fine and the coarse food may be placed in the respective compartments, and the 65 hopper may be adjusted to regulate the supply of even the coarsest kind of food without interfering with the regular discharge of the relatively fine food material. Owing to its simplicity the cost of construction is 70 slight, and it may be easily kept in a clean and sanitary condition.

Having thus described the invention, what is claimed as new, is:—

1. In a device of the class described, a 75 tray having an upstanding circumferential flange and a conical bottom portion, radially disposed wall members rising from the tray and provided at their lower ends with extended flange portions connected with the 80 circumferential upstanding flange and forming partitions, bridge members connecting said partitions, a hopper having notches at its lower edge engaging the partitions, and means for supporting the hopper at various 85 adjustments with respect to the tray.

2. In a device of the class described, a tray having wall members rising therefrom, resilient rods extending upwardly from the tray and provided with apertured plates at 90 their upper ends, and a hopper having inwardly extending pins engaging the apertured plates.

3. In a device of the class described, a tray having upstanding wall members 95 tapered upwardly and provided at their outer edges with flanges formed at an obtuse angle thereto, a slightly tapering hopper interiorly engaged by the flanges of the wall members, and means for supporting the 100 hopper adjustably with reference to the tray.

4. In a device of the class described, a tray having a circumferential upstanding flange, wall members rising from the tray and having flanges connected with the upstanding flange and forming partitions, bridge members connecting the partitions and spaced above the bottom of the tray, a hopper having notches at its lower edge engaging the partitions, means for supporting the hopper adjustably with respect to the tray, a lid for the hopper, and a guard comprising two hoops encircling, respectively, the hopper and the upstanding flange of the 110 tray, and spacing bars connecting said hoops, said guard being detachably supported on the tray.

In testimony whereof I affix my signature in presence of two witnesses.

SYLVESTER A. DRAKE.
